TUBULAR METAL CHAIR FRAME

Morton R. Cohen, Chicago, Ill.

Application February 29, 1956, Serial No. 40,411

Term of patent 14 years

(Cl. D15—1)

FIG. 1

FIG. 2

FIG. 3

Fig 1 is a plan view of a tubular metal chair frame, showing my new design;

Fig. 2 is a front elevational view; and

Fig. 3 is a side elevational view.

I claim:

The ornamental design for a tubular metal chair frame, as shown.
